UNITED STATES PATENT OFFICE.

MILTON RUSLING WOOD, OF EAST ORANGE, NEW JERSEY.

DISPLAY-CARD.

1,236,131.

Specification of Letters Patent.

Patented Aug. 7, 1917.

Application filed September 3, 1915. Serial No. 48,931.

To all whom it may concern:

Be it known that I, MILTON RUSLING Wood, a citizen of the United States, and a resident of East Orange, in the county of 5 Essex and State of New Jersey, have invented certain new and useful Improvements in Display-Cards, of which the following is a specification.

This invention relates to display cards, 10 for instance those used for advertising purposes and adapted to be held in substantially vertical positions by means of self-contained braces or easels.

These cards are usually made of paper 15 board of a minimum weight, according to the sizes of the cards, in order to minimize the cost of manufacture and of transportation to the points of use.

With the conventional weights I have 20 found that the paper board has a tendency to warp or curl, especially at the corners, or to sag by its own weight when the cards are displayed in the usual flat form, and it was in order to overcome this tendency to distortion that my invention was conceived.

Further, if of relatively great length, the 25 cards are frequently folded for packing and shipping and, when placed on display, have a tendency to bend at the line of folding, thus destroying the effect of the matter displayed thereon, and my invention likewise overcomes this tendency.

My invention is fully described in the following specification, of which the accompanying drawings form a part, in which like characters refer to like parts in each of the views, and in which:—

Figure 1 is a side view of a display card provided with my invention;

40 Fig. 2 is an enlarged section taken on the line 2—2 of Fig. 1; and

Fig. 3 is a section taken on the line 3—3 of Fig. 2 but with the upper half folded over the lower half and my invention in 45 operative.

In the drawings forming a part of this application I have shown a sheet 4 of pasteboard or the like, of any desired form, adapted to carry display matter on the front 50 thereof, an easel being provided therefor consisting of a sheet of pasteboard 5 pasted or otherwise secured to the back thereof and adapted to be folded on a line 6 thereof against the board 4 for storage or shipping, 55 and perpendicular to said board when the card is to be displayed, this being of old

and well known construction; the line 6 is preferably on the central vertical line of the card or board 4 and may be provided with a foldable leaf member 7 to serve as a brace 60 for maintaining the easel member in supporting position, as shown in Fig. 2.

The card 4 is usually supplied in flat form and is intended to be so displayed but, as stated, the weight of the upper end thereof, 65 as well as the climatic variations, causes the board or card 4 to sag, especially at the upper corners thereof, thereby destroying the effect of if not entirely concealing the display matter on the front thereof. 70

I have found by experiment that if the card 4 be flexed in a horizontal plane whereby the card is bent on a plurality of vertical lines to produce a curve therein this tendency is prevented and the card remains in 75 initial form indefinitely, regardless of climatic changes.

To obtain the best results I have found that this curvature should exist for the full width of the card and I have, therefore, 80 provided a length of cord 8, or equivalent, which I secure at the side edges of the card 4 and engage with the rear of the easel member 5 when the latter is in operative position; this curves the card 4 in the manner 85 of a bow, as clearly shown in Fig. 2, and the distortion incident to the usual flat card is avoided.

I prefer to make the cord 8 of such length as to permit flattening of the card 4 without disconnecting the cord ends therefrom, in other words the cord is of a length greater than the distance between the points of connection thereof with the card when the latter is flattened; I prefer, also, to 90 pass the cord through an opening 9 in the easel member 5, an eyelet being provided to protect said opening in the sliding of the cord therein, if desired, and it will be seen that the easel member may be moved into 100 or out of operative position without disturbing the connection of the cord with the card 4, thus rendering the card ready for instant display without the need for instructing the more or less intelligent persons placing the cards on display as to the intent or result of the cord 8. 105

With large cards, as shown, the easel member is not secured thereto for the full height thereof, thereby permitting the folding of the card 4 as on a line 10 for shipment or storage, and when the two mem- 110

bers of the card are unfolded and the easel moved into operative position, the flexing of the card by means of the cord 8 overcomes any tendency of the card to bend on the line 10 and, in fact, smooths out any wrinkles in the front of said card which had been caused by folding the same.

The degree of flexing of the card 4 is exaggerated in the drawings, as a relatively slight displacement from the flat form is sufficient and too great a degree of flexure would tend to distort the display matter or to conceal a portion thereof from one point of observation thereof, the radius of the curve being gaged according to the sizes of the cards and the weights of the materials employed.

My invention is very simple though of great advantage for the purposes stated and, while I have devoted myself to the production of display matter for many years, I have never encountered any means for accomplishing the desired results, although I am aware that cards have been held in seg-

25
mental or cylindrical shape where the nature of the display required it, but not with the easel for supporting the means for card flexing to overcome warping or distortion of the card.

Having fully described my invention, 30 what I claim as new, and desire to secure by Letters Patent, is:—

A display card, a cord connected at its ends with the edges of said card, and an easel for maintaining said card in display 35 position and for tautening said cord to flex said card to prevent distortion thereof, said easel being provided with an opening for said cord to maintain the latter in permanent connection therewith.

40
In testimony whereof I have signed my name to this specification in the presence of two subscribing witnesses.

MILTON RUSLING WOOD.
